UNITED STATES PATENT OFFICE.

WILLIAM A. TOWNSEND, OF HUGO, OKLAHOMA.

SIGN.

Application filed March 24, 1921. Serial No. 455,235.

To all whom it may concern:

Be it known that I, WILLIAM A. TOWNSEND, citizen of the United States, residing at Hugo, in the county of Choctaw and State 5 of Oklahoma, have invented certain new and useful Improvements in Signs, of which the following is a specification.

This invention relates to new and useful improvements in display signs the primary 10 object of the invention being to provide a sign which can be easily assembled with any kind of support and firmly clamped thereto.

Another important object of the invention is to provide a sign which preferably consists of an illuminated casing of a configuration causing it to snugly fit its support, whereby the sign will not be susceptible of vibration when it is used upon vehicles as it is my intention to so use the device.

Another object of the invention is to provide an illuminated sign which is of extraordinary simple construction thereby rendering the same manufacturable at a minimum cost, and which at the present time 25 possesses the rigidity and durability essential to devices of this character.

Other objects and advantages of the invention will become apparent during the course of the following description.

In the accompanying drawing forming a part of the application and wherein like numerals are employed to designate like parts throughout the several views,

Figure 1 is a perspective view of the invention in its vendable form.

Figure 2 is a transverse section of the same.

Figure 3 is a front elevation of a modified form of the sign.

Figure 4 is an end elevation of the same.

Figure 5 is a plan view of the same.

Figure 6 is an enlarged detail section of a portion of the modification.

Referring now to the drawings wherein 45 for the purpose of illustration are shown the preferred embodiments of my invention, the numeral 7 designates the sign in its entirety and which is susceptible of many applications or uses, it however being under-

stood that the device has been particularly designed for attachments to motor vehicles and preferably to the wind shields thereof whereby the indicia displayed by the sign may be readily seen by the public.

The sign preferably consists of an elongated flat rectangular casing 8, the back of

which is preferably plane so that it may fit snugly against its support.

An electric bulb support 9 is secured to the back of the casing and is positioned centrally within the casing whereby the electric lamp 10 mounted upon the bracket will shed its light evenly upon a glass plate 11 suitably retained in the open front 12 of the casing. The edges 13 of the casing 60 bordering upon the opening are turned inwardly thereof to prevent outward displacement of the glass 11, while inward movement of the latter is prevented by an inwardly extending flange 14 disposed within 65 the casing. It will of course be understood that this glass plate or translucent plate is provided with the indicia desired by the owner of the sign.

Electric wires 15 lead from a source of 75 current through the bottom of the casing to the electric lamp 10 or socket therefor and a switch 16 is interposed in the wiring whereby the light may be controlled at will.

The modification of the invention 80 embodies an inexpensive manner of retaining the glass plate 11 within the opening in the casing, and consists of providing channels in the two vertical edges and the bottom edge bordering upon the opening in the front of 85 the casing. These channels 18 are established by first bending the edges inwardly of the opening in the casing and upon each other and then bending the free edges inwardly of the opening so that they are arranged in spaced parallel relation to the portions of the edges bent upon themselves, as clearly seen in Figure 6. From this construction, it will be obvious that the glass plate 11 may be slipped into position within 90 the channels 18 from the top of the casing. As best seen in Figure 4, the ends of the top and bottom of the casing are formed with tabs 19 which are adapted to be bent to engage the exterior surfaces of the two 100 ends of the casing and are secured thereto in any suitable manner.

The means for retaining the sign upon a support consists of extending the top 20 of the casing rearwardly so that it projects 105 a substantial distance beyond the rear plane face of the casing, in the form illustrated in Figure 1. As best seen in Figure 2, a pair of arms located adjacent opposite ends of the casing depend from the top 20 in 110 spaced parallel relation to the back of the casing. These arms, it will be noted, extend

approximately the full height of the casing and each arm is provided with a pair of thumb nuts 22 which extend through the arm and on their inner end are provided 5 with heads adapted to abut the support upon which the sign is mounted. These heads may of course be provided with felt or other non-marring material and strips 23 of similar material are secured to the back 10 of the casing directly opposite the thumb screws so that the support for the sign is clamped between cushioning or non-marring elements.

The arms or depending portions 21 of 15 the casing shown in the modification are identically the same as those carried by the casing shown in Figures 1 and 2, the only difference being the arms or depending portions are not extensions or parts of an 20 extended top of the casing, but are separate elements having their upper edges angularly disposed to lie approximately in the same plane with the top of the casing. The free ends of the arms 21 depend as at 24 and 25 are arranged at right angles to the angularly disposed portion so that the arms may be secured to the back of the illuminated casing in any desirable manner. Of course, it will be obvious that these arms may be secured to the casing in most any manner just 30 so they provide a bridging or supporting portion adapted to rest upon the upper edge of a suitable support. The arms of the modification are likewise provided with 35 thumb screws the same as the other form of

invention for the same purpose. It is also within the purview of my present invention to have the arms 21 constructed of resilient material so that they together with the back of the casing form clips for frictionally engaging the support when the sign is slipped thereover. 40

The foregoing description and accompanying drawings have reference to what might be considered to be the approved or preferred form of my invention. I desire it to be understood that I may make such changes in the construction, combination and arrangement of parts, materials, dimensions, etc., as may prove expedient and fall 45 within the scope of the appended claim. 50

Having thus described my invention what I claim as new and desire to secure by Letters Patent is:

A sign comprising an illuminated casing, 55 the top thereof being extended rearwardly beyond the plane back of the casing, said extended top being provided with a depending portion arranged in spaced relation to the back of the casing, thumb screws passed 60 through the depending portion, and cushion members fastened to the back of the casing and disposed opposite the thumb screws.

In testimony whereof I affix my signature in presence of two witnesses.

WILLIAM A. TOWNSEND.
